UNITED STATES PATENT OFFICE.

WILLIAM HALKET, OF HOLYOKE, MASSACHUSETTS, ASSIGNOR TO L. D. VAN VALKENBURG, OF HOLYOKE, MASSACHUSETTS.

SPRING-CLIP.

1,387,978.

Specification of Letters Patent. Patented Aug. 16, 1921.

Application filed January 21, 1920. Serial No. 353,117.

To all whom it may concern:

Be it known that I, WILLIAM HALKET, a citizen of the United States of America, residing at Holyoke, in the county of Hampden and State of Massachusetts, have invented certain new and useful Improvements in Spring-Clips, of which the following is a specification.

This invention relates to improvements in spring clips for holding papers and small articles together and its leading object is to provide a simple device of this character constructed in two pieces one of which is provided with a spring for engaging the other, the two pieces or members being pivotally associated with each other so that the spring will exert tension against one of the members to hold terminal portions of both members toward each other, the device being so constructed that the connecting ears which permit of pivotal movement of one member on the other cannot directly engage the surface of a desk or table or other article by reason of the fact that the terminal portion of said ears is prevented from direct engagement with the desk or table surface by reason of an offset portion formed on the member engaged by said ears.

With the above and other objects in view this invention relates to certain new and useful constructions, combinations and arrangements of parts, clearly described in the following specification and fully illustrated in the accompanying drawings, in

35 which:

Figure 1 is a plan view.

Fig. 2 is a side elevation.

Referring to the accompanying drawings 5 designates one of the lever members which 40 provides a jaw 6 and a handle 7. The lever 5 is formed with trunnions 7 and 8 extending on opposite sides thereof into openings 9^a formed in the supporting ears 9 provided on the lever 10. The lever 10 also provides 45 a jaw 11 disposed in opposition to the jaw 6 and a handle 12 is disposed in opposition to the handle 7.

The member 5 is formed with a rearwardly extending spring tongue 13 prefer-

ably stamped therefrom and thus providing 50 a rearwardly extending slot 13^a. The terminal portion 13^b of said tongue has contacting engagement with the inner face of the lever member 10 and exerts a tension against said lever member to hold the jaws 55 6 and 11 normally toward each other.

The lever member 5 is formed with a raised or corrugated portion providing a reinforcing rib 14 which substantially parallels the outline of the member and which 60 is raised at its forward portion slightly above the terminal portion of the ears 9, so that said ears will not directly engage a table or desk surface. The rib is extended along the handle to reinforce the same 65 against bending. The member 10 is formed with a similar rib 10' which need not be raised as the forward portion of the rib 14.

Having described my invention I claim:

A spring clip consisting of a pair of 70 members, one of said members being provided nearer one end than the other with lateral ears provided with circular openings and the other member being provided with lateral trunnions extending into the openings of the ears and providing a pivotal connection between the two members, the first member having a handle extending rearwardly from said ears and a second member having a handle extending rearwardly 75 from said trunnions, the first member having a relatively wide flat jaw extending forwardly from said ears and a second member having a relatively wide flat jaw extending forwardly from said trunnions, said second 80 member having the body of its jaw offset to prevent the terminal portions of said ears from contacting with the flat surface on which the clip is associated, one of said members being provided with a spring 85 tongue formed integral therewith and deflected inwardly to engage the other member to maintain said jaws in contacting relation, each of the handles being connected to its jaw by a diverging portion to permit 90 of its assembly of the two members.

Signed by me at Holyoke, Mass.

WILLIAM HALKET.
